Primary Examiner — Karen E Eldridge Powers(74) *Attorney, Agent, or Firm* — Malloy & Malloy, P.A.(57) **CLAIM**

The ornamental design for a solar glove, as shown and described.

DESCRIPTION

FIG. 1 is a perspective view illustrating my design for a solar glove;

FIG. 2 is a front view thereof;

FIG. 3 is a left side view thereof;

FIG. 4 is a top view thereof;

FIG. 5 is a right side view thereof;

FIG. 6 is a bottom view thereof; and,

FIG. 7 is a rear view thereof.

The human hand and wrist shown in broken lines illustrate the environment in which the design is used and form no part of the claim.

The crosshatched pattern, although shown intermittently, is meant to represent fabric, and is understood to be distributed uniformly over the surfaces of the claimed design upon which it occurs.
